UNITED STATES PATENT OFFICE

ARTHUR B. HOWELL, OF NEW YORK, N. Y.

IMAGE AND METHOD OF MAKING THE SAME

Application filed June 29, 1929. Serial No. 374,851.

This invention relates to images and methods of making the same.

It is among the objects of the present invention to provide a novel image.

5 It is a further object of the present invention to provide a profile image.

It is another object of the present invention to provide an annular profile image.

10 A further important object of the present invention is to provide a novel method of forming images.

Other objects of the present invention will be apparent from a consideration of the following specification taken in conjunction 15 with the accompanying drawings, in which

Figure 1 is a view of the apparatus illustrating the method used in the formation of images;

Fig. 2 is a side elevation of one form of 20 the present invention, and

Fig. 3 is a similar view of a modified form of the invention.

Referring more particularly to Fig. 1 of the drawings, it will be seen that the article 25 of the present invention is preferably formed by the apparatus shown, which includes a lamp or equivalent source of light 10 from which light is adapted to be projected through a suitable lens 11. A pattern such as 30 a person or object which the image is to represent, is placed before the lens 11, as indicated at 12, whereby a shadow of the profile of the person or object is cast upon a suitable ground glass plate 13. The silhouette thus 35 cast upon the plate 13 is directed by a mirror 14 and lens 15 to a second ground glass plate 16. The material which is to be used in the formation of the image is indicated at 17 and is mounted in a suitable lathe as- 40 sembly generally indicated by the numeral 18. Under the material 17, a second source of illumination 19 is provided, which directs light through a lens 20 across the material 17 to the under side of the plate 16, whereby a 45 shadow of the material will be cast on the under side of the plate, while the shadow of the profile will be cast on the upper side of the plate. Thus they may be easily com- 50 pared and the working of the material 17 may be easily regulated so that the configura-

tion of the material will conform with the silhouette of the person or object.

From the foregoing it will readily be seen that the method steps consist in directing a beam of concentrated light across the person or object and upon a glass whereby a silhouette of the person or object will be received on the plate. The silhouette is then reflected by a suitable mirror and passed through a concentrating lens to be superimposed upon a second plate. The material is mounted in a lathe and the light is thrown across it so that a shadow of the material is superimposed on the plate with the silhouette. The material is then rotated and cut or molded so that the profile thereof conforms with the profile of the silhouette. In the case of wood, suitable wood-working tools and the conventional lathe may be utilized.

55 In connection with the apparatus or the materials used, it will be understood that the invention is not specific to the lens arrangement or to the use of wood. Certain metal or plastic compositions may be well adapted to the formation of the images, and, if desired, other means of forming the image in accordance with the profile of the silhouette may be found.

60 Referring more particularly to Fig. 2, it will be seen that the material 17 after cutting in conformity with the profile of the silhouette, will be substantially cylindrical with an annular profile formed therein. It will be seen that in horizontal cross section the image is in all places a full and complete circle and that regardless of the angle of rotation of the device, a shadow of the image will be a reproduction of the silhouette from which the device was formed.

65 Referring more particularly to Fig. 3, it will readily be seen that only fractions of the complete cylindrical image, such as shown in Fig. 2, may be used. Thus for book ends or similar ornamental devices, the image may be cut vertically to provide a semi-cylindrical profile bust or the like.

70 In connection with the images it will be understood that the invention is not confined to the use of images of busts, but may be used

for inanimate objects as well as animate objects such as persons as here illustrated.

It will be seen that the image regardless of the angle from which it is observed, presents two symmetrical profile edges and that the image will cast a shadow of the profile which is a duplication of the silhouette cast by the person or object.

From the foregoing it will readily be seen that the invention provides a novel image together with a method of forming the same, it being understood that the invention is not confined to the specific details herein enumerated and that changes and modifications in the invention may be resorted to without departing from the spirit or scope of the invention as outlined in the appended claims.

What is claimed is:

1. A method of forming images, which includes the steps of casting the shadow of a pattern for the image and the shadow of the material from which the image is to be made, and working the material for the image whereby at least one surface will have a longitudinal contour conforming with the contour of said shadow.
2. A method of forming an image, which includes the step of casting the shadow of a pattern for the image, casting a shadow of the material from which the image is to be made, and working the material until the respective shadows conform to each other.
3. A method of forming images, which includes the step of casting a shadow of the pattern for the image, projecting said shadow upon a plate, casting a shadow of the material from which the image is to be made on said plate, and working the material until the shadows coincide.
4. A method of forming images, which includes the step of projecting upon a plate the profile of a person, reflecting and concentrating the image of said profile upon a second plate, positioning a piece of material from which the image is to be made within a lathe, and casting a shadow of said material upon said second-mentioned plate, and working said material until the shadow of the material conforms with the projected shadow of the person.

Signed at New York, in the county of New York, and State of New York, this 28 day of June, 1929.

ARTHUR B. HOWELL.
